WELL PLUG

Thomas M. Ragan, Downey, Calif., assignor to
Baker Oil Tools, Inc., Vernon, Calif., a corpora-
tion of California

Application July 31, 1945, Serial No. 607,980

9 Claims. (Cl. 166—13)

1

This invention relates to well plugs, and more particularly to plugs adapted to form a bridge or barrier in well casings and similar conduits.

It is an object of the present invention to provide a bridge plug capable of being anchored in a well casing, of simple and sturdy construction, and having a relatively small overall length and mass for its load carrying capacity.

Another object of the invention is to provide an improved plug which can be lowered in a well bore on a running-in string to the desired setting point and there hydraulically anchored to a well casing by proper manipulation of the running-in string.

A further object of the invention is to provide a well plug settable in a well casing through manipulation of the running-in string, by means of which the plug is lowered in the well bore.

Still another object of the invention is to provide a well bridge plug settable by manipulation of the running-in string, in which movement of the running-in string to anchor the plug in the casing effects automatic disconnection of the string from the plug.

This invention has other objects that will become apparent from a consideration of the embodiments shown in the drawings accompanying and forming part of the present specification. These forms will now be described in detail to illustrate the general principles of the invention, but it is to be understood that such detailed description is not to be taken in a limited sense, since the scope of the invention is best defined by the claims appended hereto.

Referring to the drawings:

Figure 1 is a longitudinal section of one form of the invention, with its parts in position for lowering in a well casing;

Figure 2 is a view similar to Figure 1, showing the well plug anchored to the casing;

Figure 3 is a cross-section, taken along the line 3—3 in Figure 1;

Figure 4 is a longitudinal section of a modified form of the invention; and

Figure 5 is a longitudinal section of still another embodiment of the invention.

In the form of the invention shown in Figures 1 to 3, the bridge plug A is lowered through a well casing B on a suitable running-in string C, such as a wire line. The lower end of the line 10 is secured to a sinker bar 11 threaded into the upper sub portion 12 of the setting tool 13. The sub is suitably secured, as by welding, to the body 14 of the setting tool, which has spaced vanes 15 on its exterior for centering the apparatus in the well casing.

2

The lower end of the setting tool body 14 fits over the upper portion of a tubular plug body 16, to which it is suitably secured by one or more shear screws 17. The body has a flange abutment 18 threaded on its lower end, and a generally frusto-conical expander 19 slidably mounted on its exterior, the outer surface 20 of the expander tapering downwardly and inwardly for slidable engagement with companion tapered surfaces 21 interiorly of a plurality of segmental slips 22, whose lower ends abut or are adjacent the body flange 18. The slips 22 are held initially in retracted position by a plurality of shear screws 23 securing them to the conical expander 19.

15 A packing 24 of general cup shape is attached to the expander 19, with its base portion 25 engaging the upper end of the expander. A clamp ring 26 is pressed against the other side of the base portion 25 by a plurality of screws 27 extending through them and threaded into the upper end of the expander. The packing has an outer upstanding rim 28 slidably engageable with the wall of the casing B and an inner rim 29 slidably engageable with the exterior cylindrical surface 16a of the body 16.

20 A sleeve actuator 30 is held initially in an upward position within the body by one or more shear screws 31. Leakage therebetween is prevented by a suitable side seal 32 positioned within a groove 33 in the exterior of the sleeve and engaging the inner wall of the body 16. The lower end of the sleeve 30 projects outwardly from the body to form an outwardly extending flange 34 to which is secured spaced tension members or tie rods 35 extending freely upwardly through holes 36 in the body flange 18 and between the segmental slips 22 for threaded attachment to the lower end of the conical expander 19. Each tie rod 35 has a lower head 37 engaging the lower surface of the sleeve flange 34 and a suitable lock nut 38 engaging its upper surface, to provide rigid attachment between the conical expander 19 and the sleeve actuator 30, which prevents relative movement therebetween in both longitudinal directions.

25 A tapered seat 39 is formed in the sleeve actuator for engagement by a tripping ball 40, which may be contained within the body 16 during lowering of the tool in the well casing. A lock is also provided to prevent downward movement of the body within the expander. Specifically, such lock takes the form of one or more spaced, longitudinally extending tapered grooves 41 in the expander 19 whose base portions 42 are inclined downwardly and inwardly. A ball 43 is located in

each of these grooves, and is adapted to wedge between the exterior 16a of the body and the base 42 of the groove when downward movement of the body 16 relative to the expander 19 tends to occur, thus locking the two members together.

The tool is lowered in the well bore on the end of the running-in string C, which may be the wire line, tubing, sucker rods, or any other suitable parts, with the external rim 28 of the packing cup 24 engaging the wall of the casing B and with the shear screws 31, 23 in place to hold the parts in their initial relative positions, with the slips 22 retracted inwardly from engagement with the casing, preferably within the circumferential confines of the body flange 18. Any fluid that might be present in the well casing by-passes around and through the plug, most of it flowing upwardly through the sleeve actuator 30, disengaging and elevating the ball 40 from its seat 39, flowing around the ball, through the upper end of the body 16 into the setting tool 13, from where it passes outwardly through slots 44 in the wall of the setting tool to a point above the plug.

When the location in the casing is reached at which the plug is to be set, downward movement of the running-in string is stopped, allowing the ball 40 to rest on the sleeve seat 39. If the fluid level in the casing is high enough to provide a sufficient hydrostatic head, the running-in string C need only be elevated a short distance to trip and set the slips 22. When a sufficient hydrostatic head of fluid rests on top of the plug, a sufficient downward force is exerted on the packing cup 24 and ball closed sleeve actuator 30 to shear the sleeve screw 31 and slip screws 23, shifting the conical expander 19 in a relative downward direction along the body 16 and within the slips 22 to cause outward expansion of the latter into engagement with the casing B. Such action can occur since the fluid is prevented from moving down past the bridge plug by engagement of the outer rim 28 of the packing cup with the casing and its inner rim 29 with the body 16, and also because of the engagement of the trip ball 40 with the sleeve seat 39 and the prevention of leakage between the sleeve 30 and inner wall of the body 16 by the side seal 32. It is to be noted that the hydrostatic head of fluid is acting downwardly over substantially the entire internal area of the well casing to set the slips, since it is acting over the internal area of the body and across the annular area between the body and the well casing.

If the hole is dry, the plug can be lowered to the desired setting point and liquid dumped or pumped into the casing on top of it. Such fluid cannot flow past the plug because of the annular packing 24 and the trip ball 40. Accordingly, when a sufficient head of fluid has been placed on the plug, the sleeve screw 31 and slip screws 23 will be sheared by the weight of the fluid alone and the sleeve actuator 30 and expander 19 moved downwardly along the body 16 to expand the slips 22 out against the casing B.

The increasing of the hydrostatic head above the plug to a sufficient extent will permit an upward strain to be taken on the running-in string C, after the slips 22 have been engaged with the casing, to shear the setting tool screw 17 and allow removal of the setting tool 13 and string C to the top of the well bore. As an alternative, a downward force, such as a downward jarring, can be availed of to shear the setting tool screw 17, after the slips have been anchored to the casing.

Another method of setting the slips is to utilize a full casing of well fluid extending completely to the top of the well bore. Assuming that the casing is full of liquid, the casing head at the surface is closed when the plug reaches its setting point. The running-in string C is then elevated, which tends to elevate all of the packer or plug parts with it. Since the packing cup 24 and sleeve actuator 30 with its engaging ball 40 cannot move upwardly because of the dead column of fluid thereabove, the initial upward movement of the running-in string C causes sufficient force to be exerted to shear the screw 31 securing the sleeve actuator 30 to the body 16 and the screws 23 holding the slips 22 to the conical expander 19. Such freeing of the body 16 and slips 22 permits their upward shifting with the running-in string C, the body flange 18 moving the slips up along the tapered surface 20 of the expander 19 and into engagement with the casing. After the slips have engaged the casing, the body can no longer move in an upward direction because of the engagement of its flange 18 with the slips 22. As a result, continuation of the upward strain on the running-in string shears the screw or screws 17 securing the setting tool 13 to the body 16 and permits the setting tool and attached running-in string to be removed to the top of the well bore.

Upon anchoring of the slips 22 to the casing, the body 16 is prevented from moving in an upward direction by the engagement of its flange 18 with the lower end of the slips. Its movement in a downward direction is prevented by the wedging of the locking balls 43 between the bases 42 of the conical expander grooves 41 and the exterior 16a of the body.

In the arrangement shown in Figure 4, the plug is lowered in the casing on a tubular string 46. An imperforate setting tool 13a has its upper sub 12a threaded on the lower end of the tubular string and its body 14a welded or otherwise secured to the sub. The setting tool body is secured to the plug body 16 by one or more shear screws 17, leakage between the two being prevented by a suitable side seal 47 positioned within a groove 48 in the setting tool and engaging the exterior of the body 16a.

The modification shown in Figure 4 may be operated in the same manner as the form of invention previously described. It also lends itself to another mode of anchoring in the casing. The tripping ball 40 need not be placed in the tool preparatory to running it in the well hole, but may be allowed to gravitate down the tubing string 46, after the setting point is reached, into engagement with the actuator seat 39. Pressure is then applied to the fluid in the tubing string to shear the screw 31 holding the sleeve actuator 30 to the body and move the actuator downwardly, pulling the conical expander 19 downwardly along the body 16 through the agency of the intervening tie rods 35. Such pulling action first shears the screws 23 securing the slips 22 to the expander 19, and then moves the expander downward within the slips to shift them radially into anchoring engagement with the casing B. With pressure still imposed on the apparatus an upward strain taken on the tubing string 46 shears the screws 17 securing the setting tool to the body 16, allowing the tubing string and setting tool to be elevated to the top of the well bore. If desired, the imposition of down weight in the tubing string will shear these screws 17 to release the setting tool 13a from the plug body 16.

70
75
76

The form of apparatus shown in Figure 5 is similar to the other arrangements. A conical expander 19a is threadedly secured to a sleeve 49 slidably mounted on the body 16 to clamp a casting engaging packing cup 50 between the upper end of the expander and the flanged upper end 51 of the sleeve. Leakage between the sleeve 49 and body 16 is prevented by a suitable side seal 52 within a groove 53 in the upper end of the sleeve slidably engaging the exterior 16a of the body of the tool.

The tool is lowered through the well casing by means of a running-in string such as a tubular string 46, which is connected to the body 16 by a sub 12c threaded onto the latter, preferably through a left-hand thread connection 54. After the desired setting point has been reached, the tripping ball 40 is pumped down or allowed to gravitate through the well tubing until it engages the seat 39 at the upper end of the sleeve actuator 30, sufficient pressure then being applied to the fluid to shear the screw 31 holding the actuator to the body 16 and exerting a downward tensile force on the tension members 35, which will be transmitted to the conical expander 19a to shear the slip screws 23 and move the slips 22 outwardly into engagement with the casing. After the slips have engaged the casing the tubing string 46 is rotated to the right to unscrew the sub 12c from the top of the body 16 and permit removal of the tubing string to the top of the well bore.

In the embodiment just described, upward movement of the body 16 is prevented by engagement of the body flange 18 with the lower end of the anchored slips 22. Downward movement to any great extent is prevented by engagement of a shoulder 55 on the upper portion of the body with the upper end of the external sleeve 49.

As assurance that the slips will remain snugly in engagement with the casing in the event the body flange 18 tends to move away from the slips 22, springs 56 may be positioned within sockets 57 in this flange for engagement against the lower end of the slips, in order to prevent lowering of the slips with respect to the conical expander 19 and their inward movement from the casing.

In all forms of the invention, the tension members 35 provide a direct transmission of thrust between the sleeve actuator 30 and conical expander 19. There is no bending action on such tension members, and they can, accordingly, be made of relatively small cross-sections and still be capable of transmitting large thrusts between the sleeve actuator and the expander, to insure firm anchoring of the slips 22 in the wall of the casing B. This arrangement also permits simple tubular parts to be used, and reduces the cost of manufacturing the plug.

It is, accordingly, apparent that a simple bridge plug and method of setting the same have been provided. The plug is short in overall length, has a minimum mass of material, and is relatively inexpensive to manufacture. No special equipment is needed to set the plug in the casing; only that which is ordinarily available at well locations. In the event that pumps are not available, the plug can be anchored very simply by subjecting it to the action of a sufficient hydrostatic head of fluid, or by closing the casing head and exerting an upward lift on the running-in string. All that need be done is to commence elevating the bridge plug, and the weight of fluid itself, or the column of entrapped fluid thereabove, will shear the screws, set the slips against the casing, and auto-

matically disconnect the setting tool from the plug.

Having thus described my invention, what I claim and desire to secure by Letters Patent is:

5. A well plug adapted to be lowered within and anchored to a well casing, including a body, expander means slidable on said body and having a tapered surface inclined downwardly and inwardly, slips slidable along said tapered surface into engagement with said casing, packing means movable with said expander means and effecting a seal between said body and casing, said packing means being disposed above said tapered surface and making slidable sealing engagement with the casing during lowering of the plug therewithin, lock means between said body and expander means for preventing downward movement of said body within said expander means but allowing relative upward movement of said body within said expander means, and means for preventing downward flow of fluid through said body.
10. A well plug adapted to be lowered within and anchored to a well casing, including a body closed against downward flow of fluid therethrough, expander means slidable on said body and having a tapered surface inclined downwardly and inwardly, slips movable upwardly by said body along said tapered surface into engagement with said casing, packing means movable with said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means.
15. A well plug adapted to be lowered within and anchored in a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
20. A well plug adapted to be lowered within and anchored to a well casing, including a tubular body, expander means slidable on said body, slips cooperable with said expander means to be shifted thereby into engagement with said casing, packing means on said expander means for effecting a seal between said body and casing, means within said body for preventing flow of
25. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
30. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
35. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
40. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
45. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
50. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
55. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
60. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
65. A well plug adapted to be lowered within and anchored to a well casing, including a body closed against downward flow of fluid therethrough, expander means slidable on said body and having an external tapered surface inclined downwardly and inwardly, slips disposed around said body and expander means, frangible means securing said slips to said expander means in retracted position, means on said body engageable with said slips to disrupt said frangible means and move said slips upwardly along said tapered surface into engagement with said casing, packing means secured to said expander means and effecting a seal between said body and casing to prevent downward flow of fluid therebetween, said packing means being disposed above said tapered surface and making slidable sealing engagement with the casing during lowering of the plug therewithin, lock means between said body and expander means for preventing downward movement of said body within said expander means but allowing upward movement of said body within said expander means to shift said slips upwardly along said expander means, and means for preventing downward flow of fluid through said body.
70. A well plug adapted to be lowered within and anchored to a well casing, including a tubular body, expander means slidable on said body, slips cooperable with said expander means to be shifted thereby into engagement with said casing, packing means on said expander means for effecting a seal between said body and casing, means within said body for preventing flow of
75. A well plug adapted to be lowered within and anchored to a well casing, including a tubular body, expander means slidable on said body, slips cooperable with said expander means to be shifted thereby into engagement with said casing, packing means on said expander means for effecting a seal between said body and casing, means within said body for preventing flow of

fluid through said body, and one or more longitudinally extending tie rods connecting said flow preventing means with said expander means.

5. A well plug adapted to be lowered within and anchored to a well casing against downward movement, including a tubular body, expander means slideable on said body and having a tapered surface inclined downwardly and inwardly, slips movable along said tapered surface into engagement with said casing, packing means on said expander means for effecting a seal between said body and casing, means movable downwardly within said body for preventing downward flow of fluid therethrough, and one or more longitudinally extending tie rods connecting said flow preventing means with said expander means.

6. A well plug adapted to be lowered within and anchored to a well casing against downward movement, including a tubular body, expander means slideable on said body and having a tapered surface inclined downwardly and inwardly, slips movable along said tapered surface into engagement with said casing, packing means on said expander means for effecting a seal between said body and casing, an actuator sleeve slideable within said body, one or more longitudinally extending tie rods connected with the lower end of said actuator sleeve and with said expander means, and means for preventing downward flow of fluid through said actuator sleeve.

7. A well plug adapted to be lowered within and anchored to a well casing against downward movement, including a tubular body, expander means slideable on said body and having a tapered surface inclined downwardly and inwardly, slips movable along said tapered surface into engagement with said casing, packing means on said expander means for effecting a seal between said body and casing, an actuator sleeve slideable within said body and projecting therebelow, one or more longitudinally extending tie rods connected with said actuator sleeve below said body and extending upwardly between said slips into connection with the lower end of said expander means, and means for preventing downward flow of fluid through said actuator sleeve.

8. A well plug adapted to be lowered within and anchored to a well casing, including a tubular body, expander means slideable on said body, slips cooperable with said expander means to be shifted thereby into engagement with said casing, packing means on said expander means for effecting a seal between said body and casing, an actuator sleeve slideable within said body and having a lower outwardly extending flange, one or more longitudinally extending tie rods connected to said flange and with the lower end of said expander means, and means for preventing flow of fluid through said actuator sleeve.

9. A well plug adapted to be lowered within and anchored to a well casing against downward movement, including a tubular body having an outwardly extending flange at its lower end, expander means slideable on said body and having a tapered surface inclined downwardly and inwardly, slips movable along said tapered surface into engagement with said casing, packing means on said expander means for effecting a seal between said body and casing to prevent downward flow of fluid therebetween, said packing means making slideable sealing engagement with the casing during lowering of the plug therewithin, an actuator sleeve slideable within said body and having an outwardly extending flange below said body flange, one or more tie rods secured to said sleeve flange and the lower end of said expander means and extending through said body flange and between said slips, and means for preventing downward flow of fluid through said actuator sleeve.
